UNITED STATES PATENT OFFICE.

JOHN F. KERR, OF PATERSON, NEW JERSEY.

CHRISTMAS-TREE SUPPORT.

SPECIFICATION forming part of Letters Patent No. 685,049, dated October 22, 1901.

Application filed June 10, 1901. Serial No. 63,849. (No model.)

To all whom it may concern:

Be it known that I, JOHN F. KERR, a citizen of the United States, residing at 171 Hamilton avenue, city of Paterson, in the county of Passaic and State of New Jersey, have invented certain new and useful Improvements in Christmas-Tree Supports, of which the following is a specification, reference being had therein to the accompanying drawings.

10 My invention relates to Christmas-tree holders or supports; and it consists of a cylindrical barrel portion in which the tree stands, a circular base much greater in circumference than the barrel portion, and adjustable legs 15 adapted to lock the barrel portion and base together, substantially as hereinafter described, shown in the drawings, and pointed out in the claim.

The objects of my invention are, first, to 20 provide a cheap and durable Christmas-tree support; second, to provide a support for Christmas trees that may be put together and taken apart with facility and that may be stored away without taking up much room; 25 third, to reduce the liability of Christmas trees to topple over, and, fourth, to provide a support which will accommodate almost any tree of the various sizes used for the purposes described. I attain these objects by the 30 vice illustrated in the accompanying drawings, in which—

Figure 1 is a side view, parts being locked together and in position to receive a Christmas tree. Fig. 2 is a top or plan view with 35 the cylindrical barrel portion removed therefrom. Fig. 3 is a section of the base on the line X-X in Fig. 2, showing the holding-groove in which the foot of the leg dovetails or locks; and Fig. 4 is a vertical sectional view through 40 the barrel portion, showing it conical in shape with a tapering bore and thumb-screws.

Referring to the drawings, the ring or base A rests flat upon the floor and being a great deal larger in circumference than the barrel 45 portion B forms a broad base and with the weight of the tree in the barrel affords a firm support for the tree which is not easily upset.

The upper face of the ring-base A may be 50 flat or of any shape, ornamental or otherwise, as desired, and is provided with holding slots or sockets α , into which the feet c of

the legs C dovetail as far as the shoulders c' will permit.

The upper portion of the legs C are provided each with a segmental collar c², which are adapted to fit around the vertical portion of the barrel B under the projecting collar or shoulder b, which is formed on the barrel B.

The barrel B may be formed either with the 60 outer face of the same circumference from top to bottom, or it may be formed tapering toward the bottom, as indicated by b', and the bore of the barrel may also be formed straight or tapering. The bottom of the barrel may 65 be closed or open.

I do not wish to limit myself to any particular size or configuration of the barrel.

The barrel may be internally threaded without departing from the scope of my invention. 70

The tree when placed in the barrel may be secured therein by means of spikes or screws b², which pass through openings in the side of the barrel.

I purpose to manufacture my support in 75 various styles and sizes, both plain and ornamental.

My support is constructed wholly of metal, the various parts being cast or molded, which makes it both cheap and durable. In practice 80 it has been found to be a safe support for a Christmas tree hung with toys and lighted candles, as it is not easily toppled over on account of its weight and the broad base. The weight of the tree or the center of gravity being directly through the center and the annular shoulder of the barrel resting upon the segmental collars on the upper portion of the legs firmly interlocks the barrel, legs, and base. 85

With this description of my invention, what 90 I claim is—

As a new article of manufacture, a Christmas-tree support consisting of a barrel portion, in combination with a broad base, and legs, the whole adapted to be interlocked and 95 held together, or taken apart, substantially as set forth.

In testimony whereof I affix my signature in presence of two witnesses.

JOHN F. KERR.
